UNITED STATES PATENT OFFICE.

HERBERT WILLIAM SPILLER, OF LONDON, ENGLAND, ASSIGNOR TO S. SMITH & SONS (MOTOR ACCESSORIES) LIMITED, OF LONDON, ENGLAND, A BRITISH COMPANY.

CARBURETING DEVICE.

Application filed January 4, 1927, Serial No. 158,985, and in Great Britain January 22, 1926.

This invention is for improvements in or relating to carbureting devices and has for one of its objects to facilitate the manufacture thereof, and for another object to increase the working efficiency. The invention is an improvement in or modification of the invention described and claimed in my United States Patent No. 1,567,088, and like the carbureting device described in that specification is particularly applicable for use with internal-combustion engines, but is not necessarily restricted to that use. The carbureting device described in that specification embodies a duct block having a plurality of ducts for carbureted air each extending, separately from the others, from its intake aperture at one end of the block to its delivery mouth at a restricted portion of the lateral surface thereof, which portion is intended to face directly the intake end of the main delivery conduit, say the induction pipe of an internal-combustion engine. The delivery mouths of the ducts are situated at different positions along the length of the block and a sleeve valve movably received upon the lateral face of the block is automatically operated by variations in the pressure in the main delivery conduit to move along the block and successively cover and uncover the said delivery mouths.

In my co-pending United States application No. 6,916, filed 5th February, 1925, there is described an improved or modified construction in which each of the said ducts extends in a straight or substantially straight path without sharp twists or bends from its intake aperture to its delivery mouth.

According to the primary feature of the present invention there is provided a carbureting device which embodies the advantages described in the aforesaid specification and which is characterized in that the duct block, upon the lateral surface of which the sleeve valve is movably received, has extending into its interior a cavity constituting an air intake which is common, and large relatively, to the ducts. The carbureting device according to the invention is further characterized in that the ducts are short (and preferably straight) and lead from the said cavity to a restricted portion of the lateral surface of the duct block. By making the ducts short and by adopting the other arrangements just specified, the cast-

ing of the block is facilitated and since the carbureted air only has to pass through short ducts the frictional resistance to its travel is but small and consequently the carburetor is capable of working efficiently, even though the carbureted air is being drawn through it at a high rate in order to satisfy large demands by the engine.

A convenient construction according to the present invention comprises a duct block of general cylindrical formation which has the aforesaid air intake cavity reaching endwise into it and has the ducts extending from such cavity to the lateral curved surface of the block. The fuel supply conduits may reach transversely into the ducts between their ends.

For a more complete understanding of the invention there will now be described, by way of example only and with reference to the accompanying drawings, one constructional form of carburetor according to the invention. It is to be understood, however, that the invention is not restricted to the precise constructional details set forth.

In these drawings:—

Figure 1 is a vertical section through the carburetor taken on the line 1—1 of Figure 2.

Figure 2 is a side elevation of the duct block and certain other parts of the carburetor, and

Figure 3 is an underplan of the parts shown in Figure 2.

Like reference numerals indicate like parts throughout the drawings.

The casing of the carburetor float chamber is indicated at 10, a cylindrical duct block at 11, a casing enclosing the latter at 12, and the intake end of an internal-combustion engine induction pipe at 13. This pipe is controlled in the usual way by a throttle valve whereof the spindle is illustrated at 14. The duct block 11 has an enlargement 15 by which it is carried by the casing 12 and there is attached to an extension 16, reaching downwardly from the duct block, a portion 17 of the casing of the float chamber. Mounted to slide automatically up and down on the cylindrical surface of the duct block is a valve 18. The construction of duct block shown has four ducts 19, 20, 21 and 22 respectively which all lead to a restricted portion of the lateral surface of the duct block 11, namely the surface im-

mediately opposite to the induction pipe 13. In its upward movement the valve 18 will first commence to uncover the duct 19, then commence to uncover the duct 20, then commence to uncover the duct 21 and finally commence to uncover the duct 22, the arrangement of these ducts being such that they overlap in the sense that two of them are being uncovered at a time. The ducts 19, 20 and 21 are for the supply of carbureted air to the induction pipe while the duct 22 is for the supply of pure air. Reaching half-way into the ducts 19, 20, 21 are vertical diffuser tubes 23 which at 15 their lower ends are arranged to surround nozzles 24 leading from the float chamber. The lower ends of the tubes 23 surround the nozzles 24 in such a way as to leave an annular space 25 for air to be drawn in between the nozzle and tube so that the fuel is delivered into the duct in the form of a mist. The pure air duct 22 will be found useful in some circumstances in promoting the efficiency of the carburetor but it is not 25 essential to employ this duct.

Extending upwardly into the duct block 11 is the main air intake cavity 26. The cavity 26, as illustrated, occupies about half the cross-sectional area of the duct block 30 and reaches from the lower end thereof to the level of the upper surface of the duct 22. The ducts 19, 20, 21 and 22 can be brought very close together, but sufficient metal can easily be left between them to 35 permit the ducts to be formed by casting. The general direction of the ducts is substantially that of the adjacent part of the induction pipe 13. The cavity 26 is quite large and permits ample supplies of air to 40 reach the intake ends of the ducts and it will be appreciated that there need be no sharp bends or twists to impede the travel of the carbureted air.

I claim:

45 1. In a carbureting device, the combination of a suction chamber having a delivery passage at one side thereof, a duct block in the chamber, a cavity extending into the duct block, of relatively large cross sectional area and constituting an air intake, a plurality of separate short straight ducts

each of relatively small cross-sectional area, each extending through said duct-block from the cavity to the suction chamber in alignment with the said delivery passage 55 therefrom and a suction-operated valve movable on the duct-block to cover and uncover the delivery mouths successively.

2. In a carbureting device the combination of a suction chamber having a delivery outlet at one side thereof, a duct-block in said chamber, a plurality of short and substantially straight ducts in the block extending each separately from the others from a cavity extending into the interior of the block and constituting an air intake which is common to all the ducts and with which the intake apertures of the ducts communicate, to a delivery mouth opening in a restricted portion of the lateral surface of 70 the block and a suction-operated valve movable on the block to cover and uncover the said delivery mouths successively.

3. In a carbureting device the combination of a substantially cylindrical suction chamber, whereof one end is closed and another end is open, having a restricted delivery outlet at one side thereof, a cylindrical duct-block extending into the chamber through its open end, a plurality of short and substantially straight ducts in the block extending each separately from the others from a cavity closed at one end and extending endwise into the block constituting an air intake which is common to all the ducts and with which the intake apertures of the ducts communicate, to a delivery mouth situated opposite the restricted delivery outlet of the suction chamber, an upstanding guiding member located upon the duct-block, a suction-operated sleeve-valve movable on the duct-block and guided by said guiding member to cover and uncover successively the delivery mouths of said ducts, diffuser tubes 85 one for each duct extending each vertically into the respective duct transversely of the axis of the duct and fuel supply means common to all of said diffuser tubes and including a constant level fuel chamber.

In testimony whereof I affix my signature.

HERBERT WILLIAM SPILLER.
